(57) **CLAIM**

The ornamental design for a moisture and density nuclear gauge calibration device, as shown and described.

DESCRIPTION

FIG. 1 is a front, top perspective view of a moisture and density nuclear gauge calibration device showing our design; FIG. 2 is a bottom, side perspective view thereof; FIG. 3 is a front view thereof; FIG. 4 is a top view thereof; FIG. 5 is a side view thereof; FIG. 6 is a bottom view thereof; FIG. 7 is a side view thereof, opposite that shown in FIG. 5; FIG. 8 is a rear view thereof; FIG. 9 is a side perspective environmental view of the moisture and density nuclear gauge calibration device shown with a nuclear gauge in broken line sitting thereon for calibration; FIG. 10 is a front, top perspective view of another embodiment of the moisture and density nuclear gauge calibration device showing our design; FIG. 11 is a bottom, side perspective view thereof; FIG. 12 is a front view thereof; FIG. 13 is a top view thereof; FIG. 14 is a side view thereof; FIG. 15 is a bottom view thereof; FIG. 16 is a side view thereof, opposite that shown in FIG. 14; FIG. 17 is a rear view thereof; and, FIG. 18 is a side perspective environmental view of the moisture and density nuclear gauge calibration device shown with a nuclear gauge in broken line sitting thereon for calibration. The broken lines shown herein are for illustrative purposes only and form no part of the claimed design. The different shading on the three blocks shown in FIGS. 1–18 represent respective different visual appearances associated with different materials.
